US0D1033490S

(12) **United States Design Patent** (10) **Patent No.:** **US D1,033,490 S**
(45) **Date of Patent:** **** Jul. 2, 2024**

(54) **COOLER FENDER FRAME**

(71) Applicant: **Dometic Sweden AB**, Solna (SE)

(72) Inventors: **Samuele Meda**, Chichester (GB);
Mikael Thelin, Huddinge (SE); **Peng Wang**, Zhuhai (CN); **Steven Elliott**,
Varsity Lakes (AU)

(73) Assignee: **Dometic Sweden AB**, Solna (SE)

(**) Term: **15 Years**

(21) Appl. No.: **29/840,161**

(22) Filed: **May 26, 2022**

Related U.S. Application Data

(60) Continuation of application No. 29/785,568, filed on May 26, 2021, now Pat. No. Des. 954,764, which is

Primary Examiner — Terry A Wallace

(74) *Attorney, Agent, or Firm* — Dinsmore & Shohl LLP

(57) **CLAIM**

The ornamental design for a cooler fender frame, as shown and described.

DESCRIPTION

FIG. 1 is a front perspective view of a cooler fender frame design;

FIG. 2 is a front view of the cooler fender frame of FIG. 1; FIG. 3 is a first side view of the cooler fender frame of FIG. 1;

FIG. 4 is a second side view of the cooler fender frame of FIG. 1; and,

FIG. 5 is a top view of the cooler fender frame of FIG. 1. The broken line disclosure represents unclaimed boundary and/or portions of the cooler fender frame in which the design is embodied.

1 Claim, 5 Drawing Sheets

Related U.S. Application Data

a division of application No. 29/697,069, filed on Jul. 3, 2019, now Pat. No. Des. 920,743.

- U.S. Appl. No. 17/825,374 titled "Mobile Cooling Box with Ice Maker" filed on May 26, 2022.
- Non-Final Office Action Issued in U.S. Appl. No. 16/728,646 mailed on May 26, 2022.
- Australian Patent Application No. 2020264299 entitled "Cover for a cooler" filed Nov. 4, 2020.
- German Patent Application No. 102020213897.4 titled "Cover for a cooler" filed Nov. 4, 2020.
- Notice of Allowance Issued in U.S. Appl. No. 29/785,568 mailed on Nov. 16, 2021.
- Notice of Allowance Issued in U.S. Appl. No. 29/785,568 mailed on Feb. 8, 2022.
- Non Final Office Action Issued in U.S. Appl. No. 16/728,687 mailed on Apr. 15, 2022.
- Notice of Allowance Issued in U.S. Appl. No. 16/728,657 mailed on Mar. 24, 2022.
- Notice of Allowance Issued in U.S. Appl. No. 29/711,906 mailed on May 2, 2022.
- Notice of Allowance Issued in U.S. Appl. No. 29/785,568 mailed on Mar. 9, 2022.
- Supplemental Notice of Allowance Issued in U.S. Appl. No. 16/728,657 mailed on May 2, 2022.
- Corrected Notice of Allowance Issued in U.S. Appl. No. 29/785,568 mailed on Dec. 6, 2021.
- Supplemental Notice of Allowance Issued in U.S. Appl. No. 16/728,604 mailed on May 13, 2022.
- Notice of Allowance Issued in U.S. Appl. No. 16/728,657 mailed on Jun. 15, 2022.
- Corrected Notice of Allowability Issued in U.S. Appl. No. 16/728,604 mailed on Jul. 8, 2022.
- U.S. Appl. No. 17/872,514 titled "Mobile Cooling Box with Ice Maker", filed Jul. 25, 2022.
- U.S. Appl. No. 17/886,803 titled "Mobile Cooling Box with Handle Module", filed Aug. 12, 2022.
- Non-Final Office Action Issued in U.S. Appl. No. 16/728,623 mailed on Oct. 3, 2022.
- Non-Final Office Action Issued in U.S. Appl. No. 16/800,512 mailed on Oct. 11, 2022.
- Notice of Allowance Issued in U.S. Appl. No. 16/728,646 mailed on Oct. 24, 2022.
- Non-Final Office Action issued in U.S. Appl. No. 17/825,374 mailed on Oct. 25, 2022.
- Final Office Action Issued in U.S. Appl. No. 16/728,687 mailed on Nov. 28, 2022.
- Decision to Grant Issued in German Application No. 102020209896.4 mailed on Jan. 10, 2023.
- Final Office Action Issued in U.S. Appl. No. 16/800,512 mailed on Feb. 14, 2023.
- Notice of Allowability Issued in U.S. Appl. No. 16/728,646 mailed on Feb. 15, 2023.
- AU Patent Application No. 2019284133 entitled "Mobile cooling box with ice maker" filed Dec. 30, 2019.
- AU Patent Application No. 2019284131 entitled "Mobile cooling box with hinge moduler" filed Dec. 30, 2019.
- Design U.S. Appl. No. 29/708,156, filed Oct. 3, 2019 titled "Latch".
- Design U.S. Appl. No. 29/605,186, filed May 24, 2017 titled "Refrigerating Apparatus".
- Design U.S. Appl. No. 29/650,910, filed Jun. 11, 2018 titled "Zipper Pull".
- Design U.S. Appl. No. 29/650,906, filed Jun. 11, 2018 titled "Soft Bag Cooler".
- U.S. Appl. No. 16/728,604, filed Dec. 27, 2019 titled "Mobile Cooling Box with Handle Module".
- U.S. Appl. No. 16/728,646, filed Dec. 27, 2019 titled "Mobile Cooling Box with Air Vents".
- Design U.S. Appl. No. 29/585,279, filed Nov. 22, 2016 titled "Latch".
- Design U.S. Appl. No. 29/708,155, filed Oct. 3, 2019 titled "Latch".
- U.S. Appl. No. 16/800,512 entitled "CFX3 Protective covers—Cover for a Cooler" filed Feb. 25, 2020.
- AU Patent Application No. 2019284128 entitled "Mobile cooling box with user interface moduler" filed Dec. 30, 2019.
- AU Patent Application No. 2019284134 entitled "Mobile Cooling Box with Latch Handle Opening" filed Dec. 30, 2019.
- AU Patent Application No. 202012545 entitled "Cover for Cooler" filed May 1, 2020.
- AU Patent Application No. 202012548 entitled "Cover for Cooler" filed Apr. 30, 2020.
- European Design Application No. 007847777-0002 "CFX3 Protective covers" filed Apr. 30, 2020.
- Decision to Grant mailed in DE Patent Application No. 102019200064.9 on Jul. 31, 2020.
- Decision to Grant mailed in DE Patent Application No. 102019200063.0 on Aug. 4, 2020.
- Notice of Allowability issued in U.S. Appl. No. 17/825,374 mailed on Mar. 7, 2023.
- Corrected Notice of Allowability issued in U.S. Appl. No. 17/825,374 mailed on Mar. 16, 2023.
